BOX JIGS AND IMPROVED METHODS OF FORMING THE SAME

Arthur H. Stanton, Jr., Novelty, and Le Isle D. Noble, Hudson, Ohio, assignors to The Standard Parts Company, Bedford, Ohio, a corporation of Ohio

Filed Nov. 4, 1957, Ser. No. 694,420

2 Claims. (Cl. 77—62)

The invention relates to jigs and particularly to a new and improved box jig.

The invention also relates to improved methods of forming box jigs.

Jigs are one of various mechanical contrivances used in manufacturing. They are work-holding devices. Box jigs are one type of jigs.

The purposes of the invention are:

To provide an efficient and rugged box jig characterized by its light weight;

To provide a firm and dependable integration between aluminum walls and cast-iron corner posts of which the jig is comprised;

To effect the aforesaid integration by a simple and inexpensive procedure; and

To provide jig posts which are interchangeable.

The annexed drawings and the following description set forth in detail certain means embodying our improvements in box jigs, and certain steps exemplifying the improved method by which said box jigs are made, such means and steps setting forth, respectively, however, only one of the various forms in which the principle of the improved jig may be embodied, and only one of the various series of steps by which the improved method may be carried out.

In said annexed drawings:

Figure 1 is a perspective view of the improved box jig, a part of the jig lid being broken away;

Figure 2 is a plan view with parts broken away and an upper part of one corner of the jig in section;

Figure 3 is a vertical section, taken in the plane indicated by the line 3—3, Figure 2;

Figure 4 is a fragmentary side elevation, taken from the plane indicated by the line 4—4, Figure 2;

Figure 5 is a fragmentary plan section, taken from the plane indicated by the line 5—5, Figures 3 and 4;

Figure 6 is a fragmentary rear elevation, taken from the plane indicated by the line 6—6, Figure 2;

Figure 7 is a detail plan view of a corner post of the improved box jig indicating holes through the corner post for forming a continuous and endless cast aluminum body of the aluminum material in said holes, the walls between adjacent corner posts, and the jig floor.

Figure 8 is a detailed elevation of part of the elements shown in Figure 4; and

Figure 9 is a detailed elevation of certain of the elements shown in Figure 6.

Referring to the annexed drawings in which the several elements are indicated by the same respective numbers in the different views, the improved box jig is an integrated structure formed in a sand mold and comprised of four finished and identical interchangeable cast-iron corner posts 1 and a cubical body 2 of toughened aluminum, the latter being a hollow casting having a front wall 3, a rear wall 4, side walls 5, and a peripherally-beveled bottom floor 6. There is also a cast-iron jig lid 7 secured at the rear end of the jig by hinges 8 to a pin 13 pivotally

2

mounted in the rear corner posts 1. The front part of the lid 7 is longitudinally slotted for the accommodation of a retaining quarter-turn screw 21 engaged in the top of the front body wall 3.

5 The posts 1 which are cast first as separate units and then positioned in the mold in spaced relation to define an interior chamber are formed with a plurality of transverse spaced holes 10, each hole 10 being formed of communicating hole sections 9 formed in each of the inner faces 11 of the posts 1, Figures 5, 6, 7, 8, and 9. These hole sections 9 communicate one with the other at their inner adjacent ends so that there are continuous holes 10 through the posts 1 leading from both ends of the front and rear jig walls 3 and 4 to the respective side walls 5.

10 15 There are a multiple of these holes 10 in each post 1 and they are vertically spaced one from the other by post gussets 12. These cast-iron gussets 12 provide additional strength for the integrated cast-iron and aluminum jig. Although the interior angle between the communicating

20 25 ends of the post hole sections 9 may be any one suitable for forming in the holes 10 continuous cast aluminum integrated with the adjacent front and rear walls 3 and 4, and the side walls 5, preferably this angle is an acute one, as indicated by 15, Figure 7, whereby the strength of the jig is increased.

The corner posts 1 are formed to provide shoulders 16 upon their faces confronting the lid 7, which shoulders 16, upon the two rear posts 1, form rests for the lid 7. These posts 1 are further formed to provide shoulders 20 30 on both of their inside faces, and are dish-shaped in the central portions of their outside faces as indicated by the numerals 19.

The bottom floor 6 of the aluminum body is provided with an integral upper pad portion 17 covering the greater 35 part of the top surface of the floor 6, the marginal portion of this pad 17 being grooved downwardly, as indicated by 18, and thence forming an integral cast structure with the upright aluminum body walls 3, 4, and 5.

40 Preferably, the cast-iron posts 1 are preheated preliminarily to the casting of the aluminum walls 3, 4, and 5, the aluminum material in the holes 10, and the floor 6, such preheating not exceeding a maximum of about 700° F. Then the aluminum structure is cast, the aluminum flowing into and through the holes 10 to form a solid continuous and endless aluminum casting. Since aluminum has a higher shrinkage coefficient than cast-iron, casting of the aluminum structure draws the corner posts 1 together and results in a sure grip and tight joints between the iron corner posts and the aluminum body structure.

50 55 60 65 70 What we claim is:

1. A box jig comprised of spaced cast-iron posts each having a plurality of holes therethrough spaced one from the other by post gussets, and a cast aluminum structure having walls between adjacent posts, said structure extending through and completely filling the holes in the respective posts to form a continuous and endless aluminum body, said aluminum body having a cast jig floor, the aluminum material in the post holes intersecting two relatively angular wall faces of the respective posts, and the interior angles formed by adjacent parts of said aluminum material in the post holes being acute ones.

2. A rugged and light weight composite jig of cast-iron and cast aluminum comprising a box-like structure having a plurality of spaced cast-iron posts defining a chamber, said posts each having a plurality of holes therethrough spaced apart by post gussets, said structure also having an endless and continuous cast aluminum body providing sides for the chamber between respectively adjacent posts and extending through and completely filling the holes of the posts, said aluminum body being firmly

bound with the walls of said post holes, and a cast aluminum floor for said chamber.
